PICTURE MOUNT OR THE LIKE AND METHOD FOR MAKING THE SAME

Carroll N. Cross, Middleboro, Mass.

Application August 14, 1936, Serial No. 96,075

5 Claims. (Cl. 40—152)

This invention relates to photograph or picture mounts and frames and to a method for making the same.

It is an object of this invention to produce photograph or picture mounts and frames which will be sturdy in use and which will protect a photograph therein against dirt and damage, and which may be manufactured from inexpensive materials with great facility and at minimum expense.

Further and important objects and advantages of the invention either will be explained hereinafter, or will become apparent from a reading of the specification with reference to the drawing in which:

Fig. 1 is a progressive assembly view of the various elements comprising the mount;

Fig. 2 is a progressive assembly view illustrating advanced stages of manufacture;

Fig. 3 shows the back of a completed mount;

Fig. 4 is a sectional view taken on lines 4—4 of Fig. 3; and

Fig. 5 is a sectional view taken on line 5—5 of Fig. 3.

The mount or frame comprising this invention includes a backboard 10, a marginal spacing member 12, a face-board 13, and a face-board inlay 20.

The backboard 10 is a single sheet of wood, cardboard, paper stock, composition wood, metal, celluloid, or other suitable material. The remaining elements 12, 13, and 20, comprising the completed frame, may be constructed of any one or a combination of such materials as hereinabove indicated with reference to the backboard 10, and it is to be understood that any of the known suitable materials may be utilized in the construction of any one or all of the elements constituting the mount.

The marginal spacing member 12 is of such size as to coincide with the marginal edges of the backboard 10. The marginal spacing member 12 is cut out along the lines 11 to provide a space or well for a picture and a suitable sheet of transparent material to protect the picture.

The face-board 13, also coincident in area with the backboard 10 and the marginal spacing member 12, is provided with a cut-out portion so that only a small marginal portion of the same remains. The backboard 10, the marginal spacing member 12, and the face-board 13, are bound together along all four marginal edges by means of an adhesively attached binding member 14 which may be artificial leather, coated paper stock, or other suitable flexible material.

A face-board inlay member 20 having a margin to conform closely to the contour of the cut-out in the face-board 13, is provided with a picture display window 21, the margins of which lie within the margins of the well in the marginal spacing member 12. The face-board inlay 20 may be suitably decorated by printing, stamping, or otherwise placing on the face thereof decorative designs such as indicated at 22. The face-board inlay member 20 is suitably affixed to the face-board 13 or to the marginal spacing member 12 as by gluing, or otherwise.

In order to provide means for inserting a photograph or picture into the mount, there is provided an opening in the backboard 10. In the preferred practice of this invention a picture inserting flap is formed in the backboard 10 by cutting the backboard along three lines 16 to constitute a flap 25 which may be swung outwardly on score lines 15 along the fourth side of the flap. The flap 25 may be held in closed position by means of one or more latch members comprising a latch grommet 17, having at one end thereof a latch finger 18. The grommet 17 may be seated in either the backboard 10 or in both the backboard 10 and the marginal spacing member 12, but in any event it does not extend through the face-board inlay member 21.

The appearance of the mount may be enhanced by covering the back thereof with artificial leather or coated paper stock 23, although this is not essential.

In manufacturing this mount it has been found that the following sequence of steps can be followed to great advantage. The backboard 10, the cut-out marginal spacing member 12, and the face-board 13, are assembled in the order indicated and are either initially of the same size so that the marginal edges thereof coincide, or if this is not the case they may be cut to the same dimensions after being assembled.

The three elements 10, 12, and 13, are then bound together to form a unitary structure by means of adhesively attaching a flexible binding sheet 14 over the outer surface of the face-board 13, over all four edges of the face-board 13, over the edges of the marginal spacing member 12, over the edges of backboard 10, over the margins of backboard 10 and against the rear surface thereof.

After the boards have been assembled and bound together, the face-board 13 is cut out so that the remaining marginal portions thereof define a predetermined design. Such designs

may be ovals, rectangles, or rounded corner cut-outs, such as shown in the drawing.

After the face-board 13 has been cut out, the backboard 10 is scored along the lines 15 and 5 is cut through along the lines 16 to provide the picture inserting flap 25. At the same time the flap latch comprising the latch finger 18 and the latch grommet 17 is placed in position.

A sheet of transparent material 19, such as 10 glass, now may be placed in the well in the marginal spacing member 12, although, if desired, the transparent sheet 19 may be inserted under the flap 25 at any time after the mount has been completed.

15 A face-board inlay 20 provided with a suitable picture window 21 and preferably ornamented on its outer surface, is cut along its outer margin to fit closely the edges of the cut-out portion in the face-board 13. The face-board inlay member 20 is then assembled with the mount and 20 suitably affixed thereto as by adhesively attaching the same to the marginal spacing member 12 or to the edges of the cut-out in the face-board 13. The inlay 20 is customarily not af- 25 fixed by the manufacturer, but is sold to the photographer in unassembled condition to facilitate his use of the mount. When so received, the photographer inserts the photograph through the front of the mount before affixing the inlay. 30 The flap 25 in the backboard may be used for subsequent removal and insertion of the photograph.

It is also contemplated that the cut-out in 35 the face-board 13 may be smaller than the well in the marginal spacing member 12 so that the edges thereof will overlie the edges of the well sufficiently far to provide in themselves holding means for a picture and its transparent protective covering. Thus the inlay 20 may be elim- 40 inated.

It is understood, of course, that this mount may be provided with any of the conventional means for supporting the same, such as an easel attached to the back thereof.

45 From the above description it will appear that this invention contemplated a picture mount which comprises a plurality of relatively independent superimposed elements which are bound together only by the flexible binding member 14, 50 thus producing a mount possessing a considerable degree of flexibility. In picture mounts heretofore known, the face-board has been subjected to considerable pressure, and by virtue thereof these prior devices were often broken or 55 damaged while inserting a sheet of glass or picture. Those which escaped damage during this operation often lost their shape because of stress and strain of the picture and transparent medium enclosed in them. These objections are 60 overcome by the present invention due to the flexibility of the mount obtained by merely binding the superimposed elements together into a unit by means of the flexible binding 14.

65 Furthermore, it will be seen that the mount is completely closed along its four edges and the interior thereof is accessible only through the opening in the backboard which is normally tightly closed by means of the flap 25. Thus 70 there is no opportunity for an accumulation of dirt and dust in the interior of the frame, and consequently the picture held for display therein is perfectly protected against damage.

In so far as the method of manufacture is concerned, it will be seen that the steps comprise a 75

series of very simple operations and permit the manufacture of a mount with a variety of contrasting or ornamental inlay members.

A very useful modification of the invention is effected by joining a backboard 16 to a face-board 13, along all four marginal edges by means of an adhesively attached binding member 14, and cutting out the face-board 13 so that the remaining marginal portions thereof define a predetermined design, as in the case of the principal embodiment hereinabove described. Instead of providing a face-board inlay 20 having therein a picture window 21 as in the principal embodiment, a transparent medium, such as glass, may be provided to conform to the inner 15 edges of the face-board cut-out. Such transparent member may be suitably decorated marginally and may be attached along its edges to the face-board 13 or to the backboard 10 by any suitable means such as by gluing. 20

While a specific construction and a specific mode of operation has hereinabove been described for the purpose of illustration and example only, it is desired to include herein such changes and modifications of the invention as 25 may be included in the scope of the subjoined claims which are to be read broadly in light of this disclosure.

What I claim is:

1. A picture mount or frame comprising a 30 backboard, a cut-out face-board, a spacing member extending inwardly beyond the edges of the cut-out in said face-board interposed between said backboard and said face-board, a picture receiving well in said spacing member, a picture 35 window inlay lying in the facial plane of said face-board and having its outer margins overlying the inwardly extending portions of said spacing member and its inner margins overlying a portion of said picture receiving well, said 40 backboard, spacing member and face-board having coincident outer marginal edges, and means securing said members together.

2. A picture mount or frame comprising a 45 backboard, a cut-out face-board, a marginal spacing member extending inwardly beyond the edges of the cut-out in said face-board interposed between said backboard and said face-board, a picture receiving well in said spacing member, a faceboard inlay having a picture window smaller than said well and having marginal edges adapted to contact the margins of the 50 cut-out in said face-board, said backboard, spacing member and face-board having co-incident outer marginal edges, and means securing said members together.

3. A picture mount or frame comprising a 55 backboard, a cutout face-board, a spacing member extending inwardly beyond the edges of the cut-out in said face-board interposed between said backboard and said face-board, a picture receiving well in said spacing member, a picture window inlay lying in the facial plane of said face-board and having its outer margins overlying the inwardly extending portions of said spacing member and its inner margins overlying a portion of said picture receiving well, means in said backboard for inserting a picture or the like in said frame, said backboard, spacing member and face-board having coincident outer marginal edges, and means securing said members together.

4. A picture mount or frame comprising a 60 backboard, a cut-out face-board, a spacing mem- 70

ber extending inwardly beyond the edges of the cut-out in said face-board interposed between said backboard and said face-board, a flexible binding member disposed over the marginal edges 5 of said backboard, face-board, and spacing member whereby said members are sealed about their edges, a picture receiving well in said spacing member, a picture window inlay lying in the facial plane of said face-board and having its 10 outer margins overlying the inwardly extending portions of said spacing member and its inner margins overlying a portion of said picture receiving well, said backboard, spacing member and face-board having coincident outer marginal 15 edges, and means securing said members together.

5. In a picture mount or frame comprising a

backboard, a cut-out face-board, a marginal spacing member interposed between said backboard and said face-board, a flexible binding member disposed over the marginal edges of said backboard, face-board, and spacing member 5 whereby the same are sealed about their edges, a picture receiving well in said spacing member, a face-board inlay having a picture window smaller than said well and adapted to fit the cut-out in said face-board, an aperture in said backboard extending substantially across the width thereof, a closure for said aperture adapted to swing on score lines in said backboard, and means for normally retaining said closure in 10 closed position.
